[57] CLAIM

The ornamental design for a bottle, as shown and de-
scribed.

DESCRIPTION

FIG. 1 is a front elevational view of a bottle embody-
ing my new design;

FIG. 2 is a side elevational view thereof looking from
the right of FIG. 1;

FIG. 3 is a plan view thereof.

The rear elevational view of the bottle, not shown, is
identical to the front elevational view shown in FIG.

1. The side elevational view looking from the left of
FIG. 1, not shown, is identical to the side elevational
view shown in FIG. 2.
